COMBINED DENTAL FLOSS DISPENSER AND APPLICATOR

Charles R. Russell, 3071 Marilyn Way,
Santa Barbara, Calif. 93105

Filed Jan. 2, 1975, Ser. No. 538,471

Term of patent 14 years

Int. Cl. D24—99

U.S. Cl. D24—1 D

FIG. 1

FIG. 2

FIG. 3

FIG. 4

FIG. 5

FIG. 1 is a top view combined of a dental floss dispenser and applicator showing my new design;

FIG. 2 is a side elevational view thereof;

FIG. 3 is a left-end elevational view thereof on an enlarged scale;

FIG. 4 is a right-end elevational view thereof on an enlarged scale; and

FIG. 5 is a bottom plan view thereof.

The broken lines representing the dental floss in FIG. 1 are shown for illustrative purposes only.

I claim:

The ornamental design for a combined dental floss dispenser and applicator, as shown and described.
